United States Patent Office

Des. 219,978
Patented Feb. 23, 1971

219,978

HUMIDIFIER

John E. Reed, Glen Ellyn, Ill., assignor to Sunbeam Corporation, Chicago, Ill., a corporation of Delaware

Filed Oct. 10, 1969, Ser. No. 19,508

Term of patent 14 years

Int. Cl. D23—04

U.S. Cl. D23—146

FIG. 1 is a front elevational view of a humidifier embodying my design;

FIG. 2 is a side elevational view thereof;

FIG. 3 is an enlarged fragmentary sectional view taken along line 3—3 of FIG. 1; and

FIG. 4 is an enlarged fragmentary sectional view taken along line 4—4 of FIG. 1.

The top, rear and undisclosed side of the humidifier are flat and unornamented.

I claim:

The ornamental design for a humidifier, as shown and described.
